UNITED STATES PATENT OFFICE.

JOHN T. HORTON, OF BROOKLYN, NEW YORK.

WINDING-DRUM.

1,245,231.

Specification of Letters Patent.

Patented Nov. 6, 1917.

Application filed August 6, 1914. Serial No. 855,370.

To all whom it may concern:

Be it known that I, JOHN T. HORTON, a citizen of the United States, and a resident of New York, borough of Brooklyn, in the county of Kings and State of New York, have invented certain new and useful Improvements in Winding-Drums, of which the following is a specification.

This invention relates to winding drums and has for its object to provide a drum of the class specified, of simple and rigid construction, and one which may be constructed with a minimum of machine work thereon.

With these objects in view my improvements comprise features illustrated in their preferred embodiment in the accompanying drawing wherein the figure thereof is a front elevation of a winding drum embodying my improvements. Said figure has portions broken away to better show some features of the invention.

Drum shaft 2, which may be reduced at its ends for bearings if desired, is provided with two holes therethrough, one for pin 3 near one end of said shaft and the other for bolt 4 near the other end of said shaft. Mounted on said shaft are gear 5, adjacent to pin 3, and flange 6. Between said gear and flange is tube 7 forming the body of said drum. Gear 5, which is also a flange for one end of said drum, and flange 6 are each provided with inreaching coaxial cylindrical portions 8, 9 respectively, of a diameter equal to the inside diameter of tube 7. Said tube is carried on said cylindrical portions 8, 9 and held coaxially with shaft 2 thereby.

The several members, shaft 2, gear 5, flange 6 and tube 7 are constrained against relative rotation by the following means: 40 Hub 10 of gear 5 is provided in the end thereof with slot 11 for engagement with pin 3 in shaft 2; tube 7 is provided in the ends thereof with slots 12 and 13, respectively, for engagement with pins 14 and 15 45 projecting radially from cylindrical portions 8 and 9 of gear 5 and flange 6, respectively. Also slots 12 and 13 are preferably of such depth, from the ends respectively of tube 7, as to prevent the pins coact- 50 ing therewith from engaging the bottoms of said slots respectively.

For holding the several members, shaft 2, gear 5, tube 7 and flange 6 in endwise engagement, I provide the following means: 55 Flange 6 is penetrated by the outer ends of

eye bolts 16 and 17, arranged diametrically relatively to shaft 2. The eyes of said bolts, as 18 of bolts 16, are penetrated by and fixed to shaft 2 by bolt 4, said bolt passing through the eye of bolt 16, then through 60 shaft 2 and then through the eye of bolt 17, the whole being secured in place by nut 19 on bolt 4.

Nuts 20 and 21 of eye bolts 16 and 17 respectively are efficient for forcing flange 6 65 to the left in the figure of the drawing, thus clamping the several members in intimate engagement with each other and at the same time locating the device endwise by forcing the bottom of slot 11 of hub 10 of 70 gear 5 against pin 3 of shaft 2. Also the ends of tube 7 are forced against gear 5 and flange 6 respectively. There is thereby provided a simple, rigid and efficient winding 75 drum that can be manufactured at low cost and one which is not liable to derangement in use.

This drum may be employed in a variety of places, as for instance in hoisting derricks, and power to rotate said drum may 80 be applied to gear 5 by some well-known means not shown.

I claim:

1. A winding drum including in combination a shaft, a pair of end members on said shaft, a tube between said end members, means for supporting said tube in concentric relation to said shaft, a stop on said shaft for locating one of said end members circumferentially and lengthwise in one direction relatively to said shaft, means for preventing relative rotation between said end members and said tube, and means connected with said shaft, within said tube and effective lengthwise thereof, for forcing said 90 end members and said tube into engagement with each other and one of said end members into engagement with the stop on said shaft.

2. A winding drum including in combination a shaft, a gear and a flange thereon, a tube between said gear and flange supported in concentric relation to said shaft by said gear and flange, a pin in said shaft, a slot in said gear for engagement with said pin, means for preventing relative rotation of said gear, flange and tube, and means for holding said gear, tube and flange in endwise engagement and said gear against said pin comprising bolts fixed to said shaft 110

within said tube and having their outer ends projecting through said flange and secured thereto by nuts.

3. A winding drum including in combination a shaft, a plurality of members concentrically mounted thereon, means for preventing relative rotation of said members, means on said shaft for taking the end thrust of said plurality of members in one direction and for preventing relative rotation of said shaft and members, and means for urging said members against the end

thrust resisting means comprising bolts fixed to said shaft and nuts thereon in engagement with one of said plurality of members. 15

Signed at New York, in the county of New York and State of New York, this 4th day of August, 1914, before two subscribing witnesses.

JOHN T. HORTON.
